D. F. SMITH.

CLAMP.

APPLICATION FILED DEC. 2, 1920.

Patented Oct. 10, 1922.

INVENTOR
DANIEL F. SMITH,
by James S. Hopkins, ATTORNEY.

UNITED STATES PATENT OFFICE.

DANIEL F. SMITH, OF ST. LOUIS, MISSOURI.

CLAMP.

Application filed December 2, 1920. Serial No. 427,685.

To all whom it may concern:

Be it known that I, DANIEL F. SMITH, a citizen of the United States, residing at St. Louis, and State of Missouri, have invented 5 certain new and useful Improvements in Clamps, of which the following is a specification, reference being had therein to the accompanying drawing.

My invention relates to improvements in 10 clamps and has for its object to provide a primary clamp or vise, for saw-sharpening, joinery and like purposes, having attached thereto a secondary clamping member whereby the tool is secured to a work-bench.

15 In the drawings—

Fig. 1 is a perspective view of a clamp embodying my invention, but incompletely assembled, the lower, adjustable jaw of the secondary clamp (illustrated in Fig. 2) not 20 being in place.

Fig. 2 is a perspective view of said lower jaw of the secondary clamp.

Fig. 3 is a side elevation of the fully assembled clamp, secured to a work-bench and 25 equipped for saw filing.

In the drawings there is illustrated a work-bench top 4 having a beveled edge 5. To said top 4 the main or primary U-shaped channeled clamp 6 is secured by the lower 30 adjustable jaw 7, whose construction is shown in Fig. 2, it being formed with a slot 8, a beveled edge 9 engaging indentations 10 on the outer face of the clamp-arm 11, a bearing face 12 having a lug 13 to engage 35 with indentations 14 on the inner face of the clamp-arm 11, prongs 15—15 which straddle the clamp-arm 11, and an upturned lip 16 to engage the lower face of the bench-top 4.

Co-operating with said jaw 7 is a presser- 40 foot 17 carried by the winged screw 18, the screw 18 being seated in either of the threaded bores 19 in the bar 20, so that the presser-foot 17 may be mounted properly with reference to the location of the outer edge of 45 the surface which it is to engage; being mounted as in Fig. 3 when applied to a

beveled-edge bench top. The clamp 6 being constructed of channeled metal as shown, the clamp-arm 21 has attached to it the block 22 through which the thumb-screw 23 is 50 mounted as shown; and a screw 24 serves to loosely hold in place against the inner face of the clamp-arm 21 the block 25. The clamp-arm 11 has an inturned upper terminal 26, to the inner face of which terminal 26 the block 55 27 is secured by the screw 28 or like attaching means. The work to be held, here illustrated as the saw-blade 29, is fastened in place between the blocks 25 and 27 by the pressure of the thumb-screw 23. 60

The purpose of forming the terminal 26 as shown is to permit the adjustable jaw 7 to have clearance outside of the block 27 (see Fig. 3).

Having thus described my invention, what 65 I claim as new and desire to have secured to me by the grant of Letters Patent, is—

1. A clamp comprising a channeled U-shaped primary clamping member; opposing blocks mounted within said member; 70 a thumb-screw arranged to exert pressure upon one of said blocks; a secondary clamp comprising a bar fixed to said primary clamping member and a screw carrying a presser-foot and mounted through said bar 75 and adjustable toward and from said primary clamping member; and a jaw adjustably mounted on said primary clamping member beneath the plane of said presser-foot. 80

2. In a clamp, in combination with a primary clamping member, a secondary clamp comprising a bar carrying a presser-foot adjustable toward and from said primary clamping member; and a jaw slidably 85 mounted on said primary clamping member beneath said presser-foot with means for temporarily and rigidly holding said jaw in place upon said primary clamping member.

In testimony whereof I hereunto affix my 90 signature.

DANIEL F. SMITH.
